PIPE BENDING MACHINE

Bernard V. Elliott, Bartlesville, Okla., assignor to
 H. C. Price Co., Bartlesville, Okla., a corpora-
 tion of California

Application November 6, 1946, Serial No. 708,106

3 Claims. (Cl. 153—32)

1
 This invention relates to a machine for bending pipe, tubes, or other elongated articles and is intended more particularly for the bending of relatively large diameter pipe or the like. The machine is simple and rugged in construction and is compact and portable. It may be made up of few parts, most of which are standard shapes, making the machine economical to manufacture and service.

One of the objects of the invention is to provide a machine which may be quickly and easily arranged and clamped about the object to be bent, with few adjustments to be made in securing the device to the work in hand.

Other objects will be ascertained from the following description read in conjunction with the accompanying drawings in which one embodiment of the invention is illustrated.

In the drawings

Figure 1 is a perspective view of the machine and its prime mover;

Figure 2 is a bottom plan view of the machine showing the work clamping means;

Figure 3 is a front view of one section of the clamping mechanism, with parts shown in section;

Figure 4 is an end view of the machine showing the clamping mechanism in elevation;

Figure 5 is a detail plan view of the hydraulic mechanism for the bending arms with parts in section, showing the pivotal connection between the bending arms and the piston connecting rod; and

Figure 6 is an elevation of the device shown in Figure 5, with parts in section.

The invention comprises a substantially rectangular, vertically arranged frame A formed of vertical I-beams 1 at each end having reinforcing plates 2 welded to the sides thereof. These vertical beams 1 are joined at their upper and lower ends by horizontally extending parallel cross bars 3, 3a, which are secured by bolts to the outer and inner faces, respectively, of the vertical members 1. These cross plates have adjustment holes 4 spaced along their length for a purpose which will hereinafter be described.

The clamping and bending mechanism is composed of two similar sections, so the following description of one section thereof will suffice to explain the construction and operation of the machine.

Attached to each vertical beam 1, between the bars 3, 3a, and extending in opposite directions, are a pair of power units comprising hydraulic

2
 cylinders 5, 5a, actuated by mechanism (not shown) from the tractor diagrammatically shown at B.

These cylinders are welded to the frame as shown at 6. A connecting rod 7 extends from the cylinder and is joined by a pivotal connection including a clevis 8 and a pin 9 to the bending arms C of the clamping and bending section. The bending arms of each section comprise diverging I-beams 10, 11, reinforced in a manner heretofore described in connection with the member 4, which are joined together as shown at the cylinder end by welding or otherwise. At their other ends these diverging arms are welded or otherwise secured at spaced points to the clamping members and clamping collars. The clamping members D are formed of a pair of opposed, short, semi-circular pipe sections 12, 13, having a radius corresponding substantially to that of the pipe or other material to be bent. Each end of each pipe section 12, 13 is reinforced by radially extending rib-like, semi-circular clamping collar segments 14, 15, the corresponding pairs of which are laterally slightly offset from one another so as to permit their meeting faces to overlap at one end as at 16 in Figure 4. These overlapping faces are bored to receive a bolt or pintle 17 which passes through the clamping collars of each section and functions as a hinge member about which the clamping means pivots when opened to receive a pipe or other object to be bent. The opposite ends of these clamping collars terminate short of each other to provide a space E, as best shown in Figure 4, which is straddled by the latch fastening and tightening means. This means includes a pin 18 secured to the collar 15, an eyebolt 19 being pivoted on the pin. The bolt 19 engages a U-shaped ear 20 on the opposite collar and by means of the nut 19a the two collar segments are drawn together to grip the material to be bent.

An inner clamping member 21 is arranged between the two outer clamping members and is cut away for a portion of its circumference as at F, in Figure 2, to permit contracting of the metal being bent along the inner curve of the bend, the opposite face of the collar at G serving to control and guide the metal being stretched at the outer curve of the bend.

The entire bending and clamping apparatus is supported by a rig from the tractor B and is suspended from the boom line of the rig by a series of cables or rods 22 which are welded or otherwise joined to the apparatus at spaced

points as shown so as to support said apparatus in a balanced manner for lowering onto the work to be bent.

In operation, the apparatus is maneuvered into position over the work to be bent, or the work may be brought to the machine, as expedience dictates, and the clamping members are held open with the latching means disengaged. As the sections 12, 13, with their integral collars are dropped over the work to be bent, the latch mechanism is engaged and drawn tight by screwing nut 19a against ear 20. With the apparatus thus in position, the hydraulic unit (not shown) on the tractor is actuated to supply power to the hydraulic cylinders 5, 5a. The action of the cylinder forces the bending arms in opposite directions, the pivotal connection at 8, 9, Figure 6, permitting the bending arms to swing in an arcuate path, thereby causing the ends of the work to be brought together, forming a bend between the clamping sections. As the degree of bending angle is governed by the length of the connecting rod attached to the piston, where a short rod is used, only a short bend may be made. To permit successive bends on the work until the desired angle is obtained, the cross bars 3, 3a are provided with adjustment holes 4 by means of which the vertical beams 1 may be moved along the cross bars and secured in adjusted position by bolts or pins passing through said adjustment holes, whereupon the bending operation heretofore described may be repeated.

It will be obvious that both power cylinders may be actuated simultaneously to effect a bend, or only one may be actuated, the bending arm of the other unit remaining stationary to support the pipe.

The embodiment of the invention herein described and shown in the accompanying drawings is illustrative of one practical adaptation thereof, and it is to be understood that changes in design and construction may be made without departing from the spirit of the invention as defined by the appended claims.

I claim as my invention:

1. A machine for bending pipe and the like comprising a supporting framework, a pair of power units mounted on said framework, a bending arm secured to and actuated by each of said power units, work clamping means on said bending arms, said means comprising opposed pipe sections, a reinforcing collar segment at each end of each section, the corresponding collars of each pair being offset laterally from one another with the side, meeting faces thereof over-

lapping each other at one end, a bolt passing through said overlapping portions of each segment to serve as a pintle therefor, and means at the opposite ends of said segments for latching them together.

2. A machine for bending pipe and the like comprising a supporting framework, a power unit mounted at each end of said framework, bending means pivotally secured to each power unit arranged to be operated in opposite directions, said means including a pair of arms joined together at the power unit and diverging outwardly therefrom, work clamping means secured at spaced points to said arms, said means comprising opposed gripping sections for gripping the work, a reinforcing collar segment at each end of each section, the corresponding collars of each pair being offset laterally from one another with the side faces thereof overlapping each other at one end, a bolt passing through said overlapping portions of each segment to serve as a pintle therefor, and means at the opposite ends of said segments for latching them together about the work.

3. A machine for bending pipe comprising a frame, said frame comprising a pair of spaced vertical bars connected by a pair of spaced cross bars, a power unit connected to each of said vertical bars, a reciprocating member actuated by each of said power units, bending arms pivotally connected to each of said members, means on said bending arms for clamping said arms to the pipe being bent, whereby movement of said reciprocating members operates to bend said pipe at a point between said pipe clamping means and means for adjusting said vertical bars to spaced points along the cross bars.
